U. S. PATENT OFFICE.

No. 57.

1861.

WHOLE No. 1,422.

Label or Trade Mark.

ISAAC D. BREWER, OF CAMBRIDGE, MASS.

Letters Patent for a Design, No. 57, dated May 28, 1861.

SPECIFICATION.

TO ALL WHOM IT MAY CONCERN:

Be it known, that I, ISAAC D. BREWER, of Cambridge, in the county of Middlesex, and State of Massachusetts, have invented a new design of a trade mark for Cigar Boxes, to be applied to a brand of cigars, of which the following is a full, clear, and exact description, setting forth and defining the peculiarities of the said label or trade mark, which distinguishes it from all others.

The principal figures on the label represents the celebrated trotting mare "Flora Temple" driven in a light trotting sulky. The wheels and shafts of the sulky are red, the seat dark colored.

The driver's dress consists of dark pants, blue jacket, and red cap. The border of the label is formed of vines twined around poles, at the top are the words "Flora Temple," and beneath these the words "Fabrica de Tabacos de Superior Calidad Habana de C. B. & S. Calle del S. Mercado, No. 14."

Claim.

What I claim as my invention and desire to secure by Letters Patent, is the above described design for a label or trade mark.
